CLAIM

The ornamental design for a battery charger, as shown and described.

DESCRIPTION

FIG. 1 is a front, bottom, right side perspective view of a battery charger, showing our new design;

FIG. 2 is a rear, top, left side perspective view thereof;

FIG. 3 is a front elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines depict portions of the battery charger that form no part of the claimed design. The dot-dash broken lines represent a boundary between claimed portions and unclaimed portions of the battery charger and form no part of the claimed design.
